SCREENING AND PURIFYING MACHINE

David M. Shaler, Leavenworth, Kans., assignor of
one-half to Jennie M. Shaler, Silver Creek, N. Y.

Application October 6, 1938, Serial No. 233,668

5 Claims. (Cl. 209—28)

The invention relates primarily to machines for screening and purifying various kinds of finely divided materials and is particularly adapted for use in the milling of flour and the like. Few improvements have been made in the fundamental principles of sieve purifiers or screens in recent years. The greater number of purifiers now in use which could be classed as the conventional type, comprise a horizontal reciprocating screen 5 with traveling hair brushes to clean the screen from the underside, an air chamber above the screen, a superimposed suction fan connected to the air chamber, a hopper-like compartment below the screen terminating in screw conveyors 10 with traveling hair brushes to clean the screen from the underside, an air chamber above the screen, a superimposed suction fan connected to the air chamber, a hopper-like compartment below the screen terminating in screw conveyors 15 close to the floor to transport the finished materials from the machine, and a system of cut-off slides of fixed width to direct the materials into one conveyor or another. This type of construction requires a considerable amount of space 20 and moreover necessitates complicated transmission means for operating the brushes and the conveyors. The amount of power required to operate the machine is excessive compared to the amount of work accomplished. In this type of machine, louvre doors are provided on the sides 25 of the machine immediately below the screen to admit air under said screen, but with such means of admitting the air, there is no way to control the air to any particular section of the screen. The 30 hopper-shaped sides of the chamber below the screen become heavily coated with the material passing through said screen and channels often form in this coating causing the finished product to be diverted to the wrong conveyor, or in other words, causing a crossing of the finished stock. 35 The conveyors collect large quantities of finished product which in time become rancid and contaminated with moth webs, flour worms and larvae. The feed box in this type of machine is usually of the shaker type and is located inside 40 the machine housing in the air chamber. When making adjustments to the feed, it is necessary to open the door at the head end of the machine and when so doing, the air purifying effect is 45 suspended and the machine as a whole does not function. In this type of machine, there is no aspirating effect applied to the stock before the latter is delivered to the screening means. The screen cleaning brush generally travels from side 50 to side and in the same path, and as a consequence, excessive wear takes place and the screen cloth is often torn apart by the brush. Moreover, moth webs often form in the brush structure destroying its effectiveness and causing contamination. 55

It is the object of the present invention to provide a new and improved construction which is free from such disadvantages as those above pointed out and will operate efficiently with little attention, after initial adjustment according to 5 the stock to be screened and purified.

With the foregoing and minor objects in view, the invention resides in the novel subject matter hereinafter described and claimed, description being accomplished by reference to the accompanying drawings.

Figure 1 is a central vertical longitudinal section of the machine.

Figure 2 is a transverse sectional view on line 2—2 of Fig. 1.

Figure 3 is an enlarged fragmentary sectional view through the right hand end of the machine.

Figure 4 is a horizontal sectional view on line 4—4 of Fig. 3.

In the drawings above briefly described, a preferred construction has been illustrated, and while this construction will be rather specifically explained, it is to be understood that variations may be made within the scope of the invention as claimed.

An appropriate upstanding frame 10 is provided supported upon appropriate cushions 11 resting on a floor 12, the upper portion of said frame being provided with a covering 13 of sheet metal or the like and with appropriate doors 14 20 coacting in forming a suction hood 15 in the upper portion of said frame. Directly under this suction hood is a screen frame 16 which carries a plurality of screens ranging from relatively fine 30 at the head end H of the machine to relatively coarse at the tail end T thereof. In the present disclosure, five screens 17, 18, 19, 20 and 21 are shown, each screen being provided with an individual frame 22 resting upon suitable supporting means 23 carried by the main frame 16 and held 35 normally against upward movement by suitable removable cleats or the like 24. Obviously, any screen and its frame 22 may be removed without disturbing the others, for instance, to apply screen cloth of a coarser or finer weave, as may 40 be required.

The main screen frame 16 is supported by inclined spring arms 25 secured at their lower ends to said frame and secured at their upper ends to appropriate brackets 26 carried by the frame 10. 50 The frame 16 is provided with upwardly projecting plates 27 at its sides, connected by a transverse shaft 28. The lower ends of pitman rods 29 are connected with the shaft 28 and the upper ends of these rods are operatively connected with 55

eccentrics 30 on a transverse shaft 31 which may be driven in any preferred manner, for instance, by means of an electric motor 32 and a belt and pulley drive 33. The shaft 31 is mounted in appropriate bearings 34 carried by a transverse bar 35 forming part of the frame 10.

The top of the suction hood 15 is provided with an air outlet 36 for connection with a suction fan or conduit (not shown), and it will be seen that reduction of pressure in said hood will cause ascent of air currents through the various screens and the material thereon to purify this material. In order that this operation shall not be impaired by any air entering between the screen frame 16 and the lower end of the hood, suitable flexible curtains or the like 37 connect said frame and hood without interfering with the vibration of the frame, produced by driving of the eccentrics 30.

20 A feeder 38 of the squirrel cage type is mounted upon the suction hood 15, and the rotary feed member 39 of said feeder may well be driven by a belt and pulley drive 40 from the shaft 31. The feeder 38 is provided with a tubular discharge chute 41 which extends downwardly through the suction hood 15 and terminates slightly above a feed pan 42 which distributes the material upon the first screen 17, the lower portion of said chute 41 being provided with a flap valve 43 urged toward closed position by a weighted arm 44 and opened only by the weight of the material resting upon it, said flap valve serving to prevent the entrance of any objectionable air currents with the ingoing material. 25 Above the flap valve 43, one side of the chute 41 is provided with an air inlet 45 to which an air conduit 46 extends from the exterior of the hood 15, the outer end of said conduit being provided with a controlling valve or wicket 47. Opposite the air inlet 45, the chute 41 is provided with an air outlet 48 connected with a conduit 49 which, in the present disclosure, extends to a suction conduit 50 at the exterior of the hood 15, although said conduit 49 could be connected 30 with the air outlet 36 of said hood, if desired. The suction created in the conduit 49, creates a current of air across the chute 41, said air entering in one quantity or another according to the adjustment of the valve 47. This current of air passes through the material descending through the chute 41 and serves to initially purify the same before it is discharged onto the screen. To slow down the material somewhat and spread it out into a relatively thin vertical 35 stream to be more effectively acted upon by the air current across the chute 41, this chute is preferably provided with an inclined baffle 51 directly above the air inlet 45 and outlet 48.

40 A receiving pan 52 extends longitudinally under the screen frame 16 and is suitably secured to this frame to vibrate therewith. This pan is provided with a plurality of receiving portions 53, 54, 55, 56 and 57, disposed under the screens 17, 18, 19, 20 and 21 respectively, each of said receiving portions being provided with an individual material discharge spout 58 and with an individual air inlet 59. Suitably adjustable valves 60 are provided to control the air entering through the inlets 59, and this air ascends 45 through the various screens and the material thereon, into the suction hood 15 from which it discharges at 16, again cleaning and purifying the material being screened. By relatively regulating the valves 60 as required, the strengths 50 of the air currents flowing upwardly through the

various screens, may be varied as desired, to produce the best results.

The chutes or spouts 58 are connected by flexible sleeves 61 with discharge chutes 62, and in the latter I provide flap valves 63 urged toward closed position by weighted arms 64 and opened only by the weight of the material resting upon them, said flap valves serving to prevent any appreciable upward flow of air through the material discharging from the machine. The tailings outlet 65 is also connected by a flexible sleeve 66 with a discharge chute 67 in which is a valve 68 identical with the valves 63, preventing any appreciable amount of air from entering the suction hood 15 through said tailings outlet. 10

Each of the receiving portions 53 to 57 of the pan 52, is provided with an extensible plate 69 adjustable longitudinally of the machine, the plate 69 of the receiving portion under any one 20 of the screens being projectable partly under the next adjacent screen. Thus, if desired, part of the material which would ordinarily fall directly through this latter screen into the underlying receiving portion of the pan, will be diverted into the next receiving portion, toward the tail end T of the machine. Thus, if the material passing through the screen 17 should be found over-screened with the result that undesirably coarse particles are being received in 25 the pan portion 53, the plate 69 of the next pan portion 54 would be adjusted to partly underlie said screen 17, thus catching the relatively coarse particles passing through this screen and diverting them into the pan portion 54. Similar 30 adjustments may, of course, be made with the plates 69 of the other pan portions so that only material of the desired predetermined grades 35 will be discharged through the spouts 58.

In the present disclosure, each of the receiving portions 53 to 57 of the pan 52 is provided with a bottom 70, portions 71 of which decline to the spout 58. At the side of this spout toward the tail end of the machine, is a rather steeply inclined wall 72 which extends transversely of 45 the pan 52 throughout the width of the latter. This wall 72 is preferably apertured to provide the air inlet 59. At the opposite side of the discharge spout, each receiving portion of the pan 52 is provided with another transverse wall 73 50 less steeply inclined, and in the present disclosure, the adjustable plate 69 is slidably mounted on this wall 73, being provided with any desired adjusting means 74. The various plates 69 may be adjusted to any required extent 55 beyond the walls 72 so that they overhang the air inlets 59, and the valves 60 are preferably so located as to be always beneath said plates 69. The receiving portion 57 need not be provided with a vertical wall such as 59, the air inlet 59 for this receiving portion may be located in the bottom thereof, and the valve 60 for this air inlet opening may be disposed above the latter. It will also be clear that the receiving portion 53 under the first screen 17 is provided with no 60 adjustable plate such as 69.

In addition to providing the air admission means above described for the various receiving portions 53 to 57 of the pan 52, I preferably provide additional air inlets or wickets 75 in the 65 opposite sides of said receiving portions and controllable in any suitable way.

In operation, the motor 32 drives the eccentric shaft 31 to vibrate the screen frame 16 and the receiving pan 52, also effecting rotation of the 75

feeding member 39 of the squirrel cage feeder 38. The material is fed by this rotary member to the chutes 41, in which it descends to the feed pan 42, encountering the cross draft of air between the inlet 45 and outlet 48 during its travel and being thus subjected to an initial purifying operation. The pan 42 distributes the material evenly on the first screen 17 and the movement of the screen frame is such as to feed this material toward the tail end T of the machine. During travel of the material successively over the screens of different degrees of fineness, said material is separated into the desired different grades, which grades are received in the various pan portions 53 to 57 and discharge through the spouts or the like 58 thereof. Whenever desired, the plate 69 of any of these receiving portions of the pan 52, may be extended to a greater or lesser extent so as to divert part of the screened material passing through any of the screens, into the receiving portion of the pan under the next adjacent screen, permitting more accurate grading than otherwise possible. Moreover, the valves 60 may be adjusted to control the upward air currents to obtain the best results from these currents as they pass through the screens and the material thereon, said currents and any dust and the like with which they are laden, entering the suction hood 15 and leaving through the outlet 36. The valves 60 are of course adjustable independently of the valves or the like controlling the additional air inlets 75 and all of these valves may be adjusted by any preferred or conventional means.

The improved machine possesses numerous advantages over conventional machines such as those previously mentioned herein. The feeder 38, being of the squirrel cage type and mounted at the exterior of the suction hood 15, is readily accessible without admitting air to said suction hood or disturbing the functioning of the machine in any manner. The construction associated with the discharge chute 41 of this feeder 38, provides an effective aspirating system to remove a considerable amount of undesirable products from the material before it reaches the screening surfaces, therefore increasing the efficiency of the machine. The quality of the flour produced from the purified middlings depends largely upon the amount of ash it contains, which ash originates from the fibrous matter in the middlings. Therefore, keeping the ash-forming substances from coming in contact with the screen surface is an important advantage. As the stock or material received by the first screen is composite, containing all of the grades in its particular class, it follows that the load is heavier upon this first screen and it is therefore very desirable to be able to have a greater upward air pressure or "drop" through the screen cloth at this point, than further toward the tail where the load is lighter and the material of a coarser granulation. This regulation of the air is readily accomplished by the system of air valves above described. It is very important that the graduation of the screening surface be under fractional control the whole length of the screen, and to accomplish this, I have divided the screen surface into separate panels or sections and the receiving pan 52 into separate receiving portions or sections 53 to 57, with the slidable plates 69. The vibratory pan 52 for conveying the separated material to the various discharge spouts, is a decided improvement over the screw conveyor system as it requires practically no power to operate and it will not crush any of the material. Moreover,

being of the vibrating type, it will not become contaminated with moth webs, larvae, etc. Moreover, it is readily accessible should cleaning be necessary. The screen vibrating means is on top of the main frame, saving length in the general machine construction. Both within and without, the machine is accessible for cleaning, repairing, etc. As a whole, the machine is simple in construction, requires small space, is of comparatively light weight, substantially fire resisting, requires few repair parts, requires only a relatively small amount of power for operation, and can be constructed at a saving over the conventional type.

The general construction shown and described is preferable, but attention is again invited to the possibility of making variations within the scope of the invention as claimed.

What is claimed is:

1. A screening and purifying machine comprising a vibratory screen frame having screens ranging from relatively fine at the head end of the machine to relatively coarse at the foot end thereof, a vibratory receiving pan under and covered by said screens, said pan having a plurality of receiving portions disposed under said screens respectively, said receiving portions being provided with individual discharge spouts and with individual air inlets, means for simultaneously shaking said screen frame and said receiving pan to sift the material through said screens and prevent it from piling on said pan, a casing providing a suction hood over and in operative relation with said screens, a feeder for feeding the material to be screened and purified onto the finest of said screens, said feeder being constructed to prevent any objectionable air current from entering said suction hood with the ingoing material, means for exhausting air from said suction hood to cause air to enter said air inlets and ascend through said screens and the material thereon, valves for said air inlets to individually control the strengths of the air currents ascending through said screens, a tailings discharge spout from the coarsest of said screens, valve means for preventing entrance of air to said suction hood through this spout, and valve means for preventing entrance of air to said receiving pan through the aforesaid discharge spouts thereof.

2. A screening and purifying machine comprising a vibratory screen frame having screens ranging from relatively fine at the head end of the machine to relatively coarse at the foot end thereof, a vibratory receiving pan under and covered by said screens, said pan having a plurality of receiving portions disposed under said screens respectively, said receiving portions being provided with individual discharge spouts and with individual air inlets, some of said receiving portions being provided with screened-material diverting means adjustable longitudinally of said pan, said diverting means of the receiving portion under any one screen being projectable partially under an adjacent screen to divert part of the material passing through this latter screen into said one receiving portion, means for simultaneously shaking said screen frame and receiving pan to sift the material through said screens and to shake it from said diverting means, a casing providing a suction hood over and in operative relation with said screens, a feeder for feeding the material to be screened and purified onto the finest of said screens, said feeder being constructed to prevent any objectionable air current

from entering said suction hood with the ingoing material, means for exhausting air from said suction hood to cause air to enter said air inlets and ascend through said screens and the material thereon, valves for said air inlets to individually control the strengths of the air currents ascending through said screens, a tailings discharge spout from the coarsest of said screens, valve means for preventing entrance of air to said suction hood through this spout, and valve means for preventing entrance of air to said receiving pan through the aforesaid discharge spouts thereof.

3. A screening and purifying machine comprising a fixed upstanding frame structure having a downwardly open suction hood at its upper portion and extending throughout the width thereof, a vibratory screen frame supported within said frame structure under said hood and having screens ranging from relatively fine at the head end of the machine to relatively coarse at the tail end thereof, yieldable means supporting said screen frame within said fixed frame structure, flexible air-excluding means connecting said screen frame with the lower end of said suction hood, means mounted on said fixed frame and connected with said screen frame for vibrating the latter, a receiving pan within said fixed frame under said screen frame and secured to the latter for vibration therewith, said pan having receiving portions disposed under said screens respectively, said receiving portions being provided with individual discharge spouts and with individual air inlets, means for simultaneously shaking said screen frame and said receiving pan to sift the material through said screens and prevent it from piling on said pan, a feeder for feeding the material to be screened and purified onto the finest of said screens, said feeder being constructed to prevent any objectionable air current from entering said suction hood with the ingoing material, means for exhausting air from said suction hood to cause air to enter said air inlets and ascend through said screens and the material thereon, valves for said air inlets to individually control the strengths of the air currents ascending through said screens, a tailings discharge spout from the coarsest of said screens, valve means for preventing entrance of air to said suction hood through this spout, and valve means for preventing entrance of air to said receiving pan through the aforesaid discharge spouts thereof.

4. In a screening and purifying machine, a shallow receiving pan for screened material, said

pan having a plurality of receiving portions each provided with a bottom having a material outlet, and two transverse walls at opposite sides of said outlet, one of said transverse walls being formed with air inlet means substantially throughout its length, the other of said transverse walls being inclined, an inclined extension plate for each receiving portion slidably upon said inclined wall thereof and extensible beyond the upper end of this wall, said inclined wall of any receiving portion being joined at its upper end to said one wall of the next receiving portion whereby said extension plate of any receiving portion will overhang said one wall of the next receiving portion, an adjustably mounted valve plate under each overhanging extension plate for controlling admission of air through the air inlet means of the adjacent wall, said valve plate extending substantially throughout the width of the receiving pan, being pivotally mounted at its upper edge substantially against the overhanging extension plate and being of a height to extend to the bottom of the pan when closed, and means for creating a current of air inwardly through said air inlet means and upwardly through said receiving pan.

5. In a screening and purifying machine, a vibratory screen frame having screens ranging from relatively fine at the head end of the machine to relatively coarse at the tail end thereof, a vibratory receiving pan under said screen frame and having receiving portions disposed under said screens respectively, said receiving portions being each provided with a bottom having a discharge opening and with walls extending transversely of said pan at opposite sides of said opening, one of said walls being provided with an air inlet, the other of said walls being inclined and provided at its upper end with an inclined slidably mounted extension plate, this plate of the receiving portion under any one screen being projectable partly under an adjacent screen to divert part of the material passing through this latter screen into said one receiving portion, said walls of adjacent receiving portions being connected with each other at their upper edges, whereby the extension plate of any receiving portion projects beyond said one wall of the next adjacent receiving portion over the air inlet of the latter, and means for simultaneously shaking the screen frame and receiving pan to sift the material through said screens and shake it from said inclined wall and extension plate.

DAVID M. SHALER.
